UNITED STATES PATENT OFFICE.

JULIUS KAHN, OF YOUNGSTOWN, OHIO, ASSIGNOR TO TRUSSSED CONCRETE STEEL COMPANY, OF DETROIT, MICHIGAN, A CORPORATION OF MICHIGAN.

BUILDING CONSTRUCTION.

1,192,208.

Specification of Letters Patent. Patented July 25, 1916.

Application filed August 23, 1915. Serial No. 46,799.

To all whom it may concern:

Be it known that I, JULIUS KAHN, a citizen of the United States, residing at Youngstown, in the county of Mahoning and State of Ohio, have invented a new and useful Building Construction, of which the following is a specification.

This invention relates to a metal frame for a building, and among its important features are the following: means whereby two structural metal sections, one of which has a plurality of rows of spaced transverse slots, may be assembled and securely braced with respect to each other at points corresponding to any desired pair of transverse slots by a wedge connection, whereby the use of rivets or bolts is avoided; means whereby a third structural metal section of less dimension than the others may be connected to the two first mentioned sections by wedge means, the three sections mentioned preferably constituting the first story stud, cap plate and second story stud; and means whereby bolts may be readily substituted for the wedges if desired.

The invention also consists in the details of construction shown, described and particularly pointed out in the claims.

In the drawings, Figure 1 is a perspective view of a preferred embodiment of the invention. Fig. 2 is a vertical section through the cap plate and adjacent parts. Fig. 3 is an elevation of a floor beam and adjacent joists wherein the invention is also embodied.

Similar reference characters refer to like parts throughout the several views.

Under the ordinary base wall 1 is mounted a sill 2, preferably of pressed metal, in which are formed on opposite sides of the longitudinal center parallel rows of alined transverse slots 3, each of which preferably includes the circular or enlarged mid-portion 4. The sill may be of Z-section, in which case one flange 5 is placed so as to engage the inner surface of the wall, the other flange 8 being extended upwardly in the plane of the outer wall surface. Rising from the sill is the stud (of substantially the same transverse width as the sill) that includes the web 12, the side flanges 13 and, preferably, the in-turned edge flanges 14, the latter of which not only stiffen the stud but engage the sill to insure a proper bearing. The stud has struck therefrom near

its ends rows of transversely alined stirrups 15, the spacing of which corresponds to that of the rows of slots in the sill, and is perforated between the stirrups of each row for a purpose hereinafter indicated. Flat 60 metal connectors having ends 20 extending longitudinally beneath the sill also have shanks 21 that pass through correspordng slots of each row and upwardly between the pairs of stirrups and the web of the stud; 65 these shanks are perforated between the stirrups of each row, and a two-armed wedge 24 (one arm 25 of which is sharpened and bites into the upper surface of the sill, the other arm being tapered) is driven through 70 the perforation in the stud and through that in the shank of the connector. These perforations are so located as to allow the wedge to draw the connector firmly into engagement with the lower face of the sill, 75 or, in other words, so as to draw the sill and the stud together. When the parts are thus joined, the arms 25, together with the web of the stud and the in-turned flanges 14, form 80 a broad bearing and prevent the stud from swinging longitudinally on the sill in one direction, and also afford a very rigid joint as concerns lateral swinging stresses; and the ends 20 stiffen the stud against swinging longitudinally in the reverse direction. 85

The studs 12—13—14 (but one of which is shown) extend from the sill to the next story of the building and are there surmounted by the longitudinal cap 26 (preferably of channel cross-section) having 90 down-turned flanges 27 that embrace the sides of the studs. The cap is also provided with rows of transverse slots 3—4 that correspond to the slots in the sill. At the upper ends the studs are perforated and have stirrups 15; and a connector 20—21, 95 that passes through one of the slots 3, is secured in position by a wedge 24, the construction and purpose of these elements being the same as previously described with 100 reference to the joints between the stud and the sill.

Rising from the cap in alinement with the outer side of the stud 12—13—14 is a second story stud of less transverse depth 105 than the former that includes the web 29, side flanges 30 and (preferably) the in-turned edge flanges 31. The second story stud is provided with a single row of stirrups 15 and a flat metal connector 32, that 110

differs from the connector 20—21 merely in the length of the shank, passes through the outer rows of stirrups on the stud 12—13—14, through one of the slots of the outer row in the cap and through the stirrups in the stud 29—30—31, a two-armed wedge 24 serving to clamp the parts together as before.

One use of the enlarged portion 4 of the slots is shown in Fig. 1, wherein a splice plate 35 is secured in position by bolts 36. Other uses are obvious—for example, the connectors may have their ends 20 placed above the sill and bolted thereto directly through the holes 4. It will be understood, of course, that the provision of the series of slots allows the studs to be located at practically any desired spacing along the sill.

The invention is also applicable to floor beam and joist connections. In Fig. 3 a floor beam formed of two pressed channel sections 40 riveted together back to back, supports on one side a pressed channel joist 41 of a given depth and on the opposite side an opposed pressed channel joist 42 of lesser (preferably half) depth. The floor beam is provided with two rows of slots (not shown) corresponding to the slots 3—4, through the upper of which passes a connector 32 that serves to join the two joists, and through the lower of which passes a connector 20—21. Two armed wedges 24 clamp the parts together as in the case of the studs and cap plate.

It is clear that the arrangement of the members is subject to wide variation, and the present illustrations are to be taken, therefore, as diagrammatic. Consequently, I do not wish to be limited otherwise than as indicated by the subjoined claims.

I claim:—

1. In a building structure, a metal bar having two transversely alined spaced stirrups near one of its ends, a second metal bar extending across the end of the first bar, said second bar having a pair of transversely alined transverse slots spaced from each other to correspond to the spacing of the stirrups, a third metal bar alined with the first bar and engaging the second bar from the opposite side, said third bar having a transverse stirrup near its end, a pair of connectors, one passing through one of the stirrups on the first bar and one of the slots in the second bar, the other passing through the second stirrup on the first bar, through the second slot in the second bar and through the stirrup on the third bar, and wedges engaging the connectors for clamping the parts together.

2. In a building, a metal stud having two transversely spaced stirrups near its upper end, a metal cap plate surmounting the stud and having a pair of transversely alined transverse slots spaced from each other to

correspond to the spacing of the stirrups, a second metal stud of lesser transverse dimension than the first mentioned stud and rising from the cap plate, said second bar having a transverse stirrup near its end, a pair of connectors, one passing through one of the stirrups on the first mentioned stud and through one of the slots in the cap plate, the other passing through the second stirrup on the first mentioned stud, through the second slot in the cap and through the stirrup on the second stud, and wedges engaging the connectors for clamping the parts together.

3. In a building structure, a metal bar having two transversely alined spaced stirrups near one of its ends, a second metal bar extending across the end of the first bar, said second bar having a pair of transversely alined transverse slots spaced from each other to correspond to the spacing of the stirrups, a third metal bar alined with the first bar and engaging the second bar from the opposite side, said third bar having a transverse stirrup near its end, a pair of connectors, one passing through one of the stirrups on the first bar and one of the slots in the second bar, the other passing through the second stirrup on the first bar, through the second slot in the second bar and through the stirrup on the third bar, and wedges engaging the connectors for clamping the parts together, said wedges engaging the second bar at points removed longitudinally from the slots whereby bracing against swinging is secured.

4. In a building structure, a metal bar having two transversely alined spaced stirrups near one of its ends, a second metal bar extending across the end of the first bar, said second bar having a pair of transversely alined transverse slots spaced from each other to correspond to the spacing of the stirrups, a third metal bar alined with the first bar and engaging the second bar from the opposite side, said third bar having a transverse stirrup near its end, a pair of connectors, one passing through one of the stirrups on the first bar and one of the slots in the second bar, the other passing through the second stirrup on the first bar, through the second slot in the second bar and through the stirrup on the third bar, and wedges engaging the connectors for clamping the parts together, said first bar including a flange and said third bar including a flange in the same plane with the flange on the first bar.

5. In a metal structure, the combination of a pair of structural members engaging at an angle, one having a plurality of rows of alined transverse slots and the other having a plurality of struck-up stirrups spaced to correspond to the spacing between the rows of transverse slots, a plurality of con-

nectors, each extending beneath a stirrup and through the corresponding slot, and a plurality of two-armed keys, each having a wedge-shaped arm engaging the corresponding connector and one structural member to force it against the second and each having another arm provided with a pointed end adapted to engage the second member a distance from said slot, whereby swaying of one member either longitudinally or transversely in respect to the other is prevented.

6. In a metal structure, the combination of a plurality of perforated flat-sided bars engaging each other at an angle, the perforations in one of the bars being in the form of a plurality of rows of transversely extending slots, connectors lying against a flat side of one of the bars and extending, respectively, through the corresponding transverse slot in the other and having the extending ends bent over to prevent movement out of said slots, and a pair of two-armed wedges each having one arm extending through a slot in one of the bars and through a slot in one of the connectors to force the bars together, the other arm extending into engagement with the bar that has the slots through which the connectors pass, whereby bracing of the parts is secured.

7. In a metal structure, the combination of a pair of bars each having a web and a flange, one of said bars having a pair of transverse slots alined transversely thereof and the other having a plurality of stirrups struck from its web at an angle to its flange, a plurality of connectors each of which extends through beneath the corresponding stirrup and through the corresponding transverse slot, and means engaging the connectors and one of the bars to force it against the other bar, whereby lateral tip-

ping of the bars with respect to each other is avoided.

8. In a metal structure, the combination 45 of three bars, the first and third bars being arranged to intersect the second and the latter having a pair of transversely alined transverse perforations, the first bar being of greater transverse dimension than the third, a pair of transversely spaced stirrups formed on the first bar, a transverse stirrup formed on the third bar, and a pair 50 of connectors, one of which passes through one of the slots in the second bar and through one of the stirrups in the first, the other connector passing through the other slot in the second bar, through the stirrup on the third bar, and through the remaining stirrup on the first bar, whereby the bars 55 are held together.

9. In a metal structure, the combination of three bars, the first and third bars being arranged to intersect the second and the latter having a pair of transversely alined 65 transverse perforations, the first bar being of greater transverse dimension than the third, a pair of transversely spaced stirrups formed on the first bar, a transverse stirrup formed on the third bar, and a pair of 70 connectors, one of which passes through one of the slots in the second bar and through one of the stirrups in the first, the other connector passing through the other slot in the 75 second bar, through the stirrup on the third bar and through the remaining stirrup on the first bar, and wedges passing through the connectors and engaging with the second bar, whereby the bars are rigidly clamped 80 together.

In testimony whereof I have signed this specification.

JULIUS KAHN.
